EMILE GRASSOT, OF MEUDON, FRANCE, ASSIGNOR, BY MESNE ASSIGNMENTS, TO
GENERAL ELECTRIC COMPANY, A CORPORATION OF NEW YORK

DEVICE RESPONSIVE TO UNBALANCED ELECTRIC CURRENTS OR VOLTAGES

Application filed August 13, 1926, Serial No. 129,032, and in France December 23, 1925.

In measuring apparatus, in relays and in devices for line protection which take into account unbalanced voltage or current, the equivalence between a system of any q vectors which are concurrent and situated in one plane and q systems each made up of q symmetrical vectors (systems of balanced vectors) is made use of. These vectors represent components of electric quantities, such as polyphase alternating voltages, currents, ampère-turns, fluxes or magnetic fields etc. according to the case in point.

In one of these systems, termed positive phase sequence system, two vectors bearing consecutive numbers form between them an angle

$$\frac{2\pi}{q}$$

20 in the positive direction; in another termed negative phase sequence system, two vectors bearing consecutive numbers make between them an angle of

$$\frac{2\pi}{q}$$

25 in the opposite direction to the preceding one.

In order to obtain the positive or negative phase sequence components of the currents, voltages, powers, etc. or of the functions of these measures, circuit arrangements are generally utilised. The system from which the symmetrical components are thus obtained 35 has the same number of phases as the basic system.

Thus, for example, in the case of a system of three-phase currents the positive or negative phase sequence components of ampère-turns forming part of a three-phase system etc. can be obtained.

It may be of interest to obtain the positive or negative phase sequence components (or functions of these components) pertaining to a system with a number of phases differing from that of the given system, for example, for protecting or measuring a three-phase system, the positive or negative phase sequence components (or functions of these

components) in a two-phase system unbalanced to the same extent

$$\epsilon = \frac{I}{D}$$

55 as the three-phase system under consideration (D being the length of one of the vectors of the positive system and I the length of a vector of the negative system).

In this connection, the given system of voltages or currents (generally taken to be q -phase) will be converted into a system of currents, voltages, ampère turns, fields or magnetic fluxes, etc. with a number of phases q' differing from q , unbalanced to the same extent as the given system, that is the ratio of the positive and negative phase sequence components of each system is the same, and then suitable circuit arrangements will be applied to this latter enabling its positive or negative 70 phase sequence components or functions of these components to be obtained; or else circuit arrangements will be used starting from a q -phase system of voltages or currents enabling the positive or negative phase sequence 75 components (or functions of these components) to be obtained directly from a q' -phase system unbalanced to the same degree as the first.

The present invention comprises line protecting devices, relays, and measuring apparatus and devices, in which the want of balance of the circuits or lines characterized by the application of the principles indicated above, i. e. by the use of devices—certain of 80 which are known (the Scott system rotating field phase transformers, etc.) plays a part enabling the positive or negative phase sequence components (or functions of these components) of a system with a number of 85 phases differing from that of the circuit to be protected or on which the measurements are taken, to be obtained.

The number of phases of the intermediary system, will be chosen so as to simplify the 95 construction of the apparatus or of the circuit arrangements. Further, the passing from one system to another can be made outside or inside the apparatus or device.

90 In order to make the bearing of the invention 100

tion readily understandable, a few examples of its application will be given hereunder.

In these examples it will be assumed that measurements are to be made on a three-phase system or that a three-phase circuit is to be protected, and that the three-phase system of currents and voltages is transformed into a two-phase system of currents, voltages, ampère-turns, fluxes or magnetic fields, etc., or that the positive or negative phase sequence components of these values or of the active, reactive or complex power in the latter system are obtained.

This transformation enables the essential properties of two-phase systems to be utilized; viz: to have only two vectors which, in balanced systems, are 90° out of phase with each other.

In the accompanying drawings:

20 Fig. 1 shows the wiring diagram of a current responsive device of the induction type.

Fig. 2 shows the wiring diagram of a current responsive device used in conjunction with a current transformer.

25 Fig. 3 shows the wiring diagram of a current responsive device similar to that shown in Fig. 1 using two transformers.

Fig. 4 shows the wiring diagram of a current responsive device using three transformers.

Figs. 5 and 6 show the wiring diagram for voltage responsive devices.

Fig. 7 shows the wiring diagram of another current responsive device.

35 Figs. 8, 9 and 10 are vector diagrams of current, voltage ampère-turns etc. components.

Figs. 11, 12 and 13 show wiring diagrams for wattmetric responsive devices.

40 Fig. 14 illustrates diagrammatically a modification of my invention.

Fig. 1 shows the wiring diagram of a relay or current responsive apparatus, of the induction type in which a torque proportional 45 to $I_d^2 + I_i^2$ is obtained, I_d being the positive phase sequence component, I_i the negative phase sequence component of the three-phase system of currents (i_1, i_2, i_3).

Now, in a three-phase circuit:

$$50 \quad 3(I_d^2 + I_i^2) = I_1^2 + I_2^2 + I_3^2$$

I_1, I_2, I_3 being the virtual or effective values of the three currents, i_1, i_2, i_3 . In order to obtain $I_d^2 + I_i^2$, it would thus be necessary to 55 use three identical electro-magnets acting on the same metallic disc D and giving torques proportional to the squares of the currents, viz; I_1^2, I_2^2, I_3^2 through the coils of which the three currents would thus flow.

60 With the wiring arrangement shown in Fig. 1 the current i_1 flows through the coil a of an electro-magnet, whilst a second electro-magnet has two windings b b' through which the currents i_2 and i_3 flow, the windings being so arranged that the ampère-turns oppose

each other. The net ampère-turns are thus proportional to $(i_2 - i_3)$. If the three-phase circuit is balanced, the ampère-turns of the two electro-magnets are in quadrature. If n be the number of turns of one of the coils of the coils b or b' and $n\sqrt{3}$ the number of turns of the coil a, the ampère-turns $n_i_1\sqrt{3}$ and $n(i_2 - i_3)$ are equal in virtual value and are in quadrature, when the currents i_1, i_2, i_3 make up a balanced system.

70 In this case a two-phase system of ampère-turns is obtained which is balanced at the same time as the three-phase system of currents and the torque given by the two suitably arranged electro-magnets will be proportioned to: $I_d^2 + I_i^2$.

75 The transformation into two-phase has thus enabled the apparatus to be simplified by replacing three electro-magnets by two only; the transformation from three-phase to two-phase is brought about within the apparatus.

80 Fig. 2 shows a wiring arrangement in which the transformation occurs outside the electro-magnets.

85 Two electro-magnets a and b act on the disc D, and through the winding of a the current i_1 flows, while through the winding of b there flows the current supplied by the secondary of a current transformer T comprising two 95 identical primaries p_1 and p_2 through which the currents i_2 and i_3 flow respectively in opposite directions.

90 If the transformer T is designed so that for a balanced system of three phase-currents the current i' in the secondary S has the same virtual value as the current i_1 , the current system i_1 and i' will constitute a two-phase system, and it will be possible for the electro-magnets a and b to be identical.

100 Fig. 3 shows a wiring diagram similar to Fig. 1, using two current transformers T and T'. D is the disc, a an electro-magnet, and b b' the double winding of a second electro-magnet.

105 The currents of the secondaries S S' of the transformers T T' flow in opposite directions through the coils b b', and the sum of these currents flows through the winding a.

110 Fig. 4 shows a wiring diagram with three current transformers T_1, T_2, T_3 . Through the coil of the electro-magnet a a current proportional to i_1 flows and through the coil of the electro-magnet b a current proportional to $(i_2 - i_3)$. If the coil b has n turns and if the coil a has $n\sqrt{3}$, the ampère-turns of the two windings form a balanced two-phase system, when the three-phase system of the currents i_1, i_2, i_3 is balanced.

115 In this figure there has been represented a circuit-breaker actuating device which may be likewise used in connection with the other relays about to be described, when it is desired to protect a circuit instead of effecting

measurements of one or other of its electrical quantities. Such device is constituted by a trip-coil P excited by an auxiliary source of current Q and mounted in a circuit adapted to be closed and opened by a switch comprising two metallic strips C which can be connected together to close the trip-coil circuit, by a finger R connected to the rotating disc D which moves said finger into and out of contact with the metallic strips CC. The trip-coil P actuates a solenoid which in its turn is adapted to operate a circuit-breaker Z mounted in the main circuit.

Figs. 5 and 6 show wiring diagrams for voltage responsive apparatus. In Fig. 5 the three-phase voltage systems of the circuits 1, 2 and 3 is converted into a two-phase system by means of a Scott device, the primaries of which are A B and C D, and the secondaries $\alpha \beta$ and $\gamma \delta$. The disc D is subjected to the influence of the electro-magnets a and b , which may be identical if the correct transformation ratios of the Scott system have been suitably chosen, and 1, 2, 3 are the three wires of the three-phase circuit.

In Fig. 6 two voltages in quadrature are obtained when the three-phase voltages are balanced. These are the voltages between the points A B and between the points C D. The latter is used directly for the winding b but the first is transformed by means of the transformer A B, $\alpha \beta$ to feed the winding a .

The transformers can also be completely suppressed; further the device can be combined with single or three-phase voltage transformers.

Fig. 7 shows the wiring diagram of a current relay or measuring apparatus, of induction type, having a torque which is a function of $(I_d^2 - I_i^2)$, I_d and I_i being the positive and negative phase sequence components of the three-phase system of currents (i_1, i_2, i_3).

A single electro-magnet is provided, which acts on the disc D. This electro-magnet may be of the wattmetric type and, as shown, comprises a coil a through which the current i_1 flows and a coil with two windings b b' through which currents i_2 and i_3 flow in opposite directions, the net ampère-turns of which are proportional to $(i_2 - i_3)$. Arrangements are made so that each coil a and $(b \ b')$ acts on the currents which the other induces in the disc D. For a system of balanced three-phase currents (i_1, i_2, i_3) the ampère-turns of the coils a and $(b \ b')$ are in quadrature. By suitably choosing the number of turns a two-phase system will be obtained.

If I'_1 and I'_2 are the virtual values of the currents of the two-phase system, and α' the angle between their representative vectors, it is easily shown that the torque of the apparatus is proportional to $I'_1 I'_2 \sin \alpha'$ and that this value is proportional to $(I'_d)^2 - (I'_i)^2$ in which expression I'_d and I'_i are the positive and negative phase sequence com-

ponents of the two-phase system. This difference is also proportional to $I_d^2 - I_i^2$.

In order to obtain the two-phase system, the same methods can be made use of as in the cases studied above. Following the same principles voltage measuring apparatus can be designed for example, according to the wiring diagrams of Figs. 5 and 6, but by arranging the windings a and b on an electro-magnet like that in Fig. 7.

As shown in Fig. 14, a group of electro-magnets a, b can be caused to act on the same movable equipment, shown as induction discs D, D'', to give a torque equal to $k (I_d^2 + I_i^2)$ and an electro-magnet $a'' b''$ to give a torque equal to $k' (I_d^2 - I_i^2)$.

If $k = \pm k'$, a resultant torque proportional to I_d^2 or to I_i^2 is obtained, according to whether the component torques add up or subtract.

If $k = k'$, the resultant torque will be zero for a certain relation between I_d and I_i , and an apparatus will be obtained the operation of which will depend on the degree of out of balance

$$\epsilon = \frac{I_t}{I_d}$$

Devices can be provided allowing k and k' or their ratio to be varied. This control can be obtained by variation of the electro-magnet air-gaps, by reactance coils, capacities, mutual induction coils, transformers, etc.

In Fig. 8, let X_1 and X_2 be the two vectors of a two-phase system. The positive phase sequence component of the vector X_1 will be:

$$2X_{1d} = X_1 + jX_2,$$

where $j = \sqrt{-1}$ and the negative phase sequence component:

$$2X_{1i} = X_1 - jX_2.$$

For vector X_2 , the positive phase sequence component will be

$$2X_{2d} = X_2 - jX_1 = -j(X_1 + jX_2) = -2jX_{1d};$$

similarly the negative phase sequence component will be:

$$2X_{2i} = X_2 + jX_1 =$$

$$j(X_1 - jX_2) = 2jX_{1i}.$$

From these formulae, twice the positive phase sequence components $2X_{1d}$ and $2X_{2d}$ are obtained, by adding to X_1 a vector jX_2 equal to $\frac{\pi}{2}$ in order to obtain $2X_{1a}$,

and by adding to X_2 a vector $-jX_1$ equal to $\frac{\pi}{2}$ in order to obtain $2X_{1i}$.

X_2 and lagging $\frac{\pi}{2}$ in order to obtain $2X_{1i}$ (Fig. 9). In order to obtain the negative phase sequence components vectors are added

to X_1 and X_2 respectively equal to and directly opposite to those used for the positive phase sequence components (Fig. 9).

- 5 In certain cases, for example when X_1 and X_2 represent currents, it is not handy to obtain the values represented by the vectors jX_1 , jX_2 or $-jX_1$, $-jX_2$. But it can be noticed (Fig. 9) that the positive and negative phase sequence components of X_1 are obtained by 70
10 adding geometrically to a vector equal to X_1 , a vector of length X_2 making with it an angle 75

$$15 \quad \left(\frac{3\pi}{2} - \alpha \right) \text{ and } \left(\alpha - \frac{\pi}{2} \right)$$

respectively in a suitable direction; similarly, in order to obtain the positive and negative phase sequence components of X_2 , a vector of length X_1 is added geometrically to X_2 and 80
20 making with X_2 angles of 85

$$\left(\frac{3\pi}{2} - \alpha \right) \text{ and } \left(\alpha - \frac{\pi}{2} \right)$$

25 respectively in a suitable direction.

Often the length of X_{1d} or X_{2d} only is required, or of X_{11} or X_{21} ; in this case, to obtain for instance the positive phase sequence component a vector X'_1 can be taken instead of X_1 , of length kX_1 equal to or proportional to the length of X_1 and out of phase with respect to it by an angle β (Fig. 10) lagging for example; if a vector X'_2 is added to it of length kX_2 equal or proportional to X_2 , with the same coefficient of proportion, but leading by 90

30 $\frac{\pi}{2}$ with respect to X'_2 hence by $\left(\frac{\pi}{2} - \beta \right)$ with 95

35 respect to X_2 , the resultant of the two vectors thus obtained (Fig. 10) will give a vector X_{1d} of length kX_{1d} equal or proportional to X_{1d} and lagging it by angle β . 100

Similar remarks can be made concerning the other components of X_1 and X_2 .

40 45 From these remarks it follows that values can be obtained equal to or proportional to the positive and negative phase sequence components of the given out of phase values by producing suitable phase-displacements, 105
50 leading or lagging, of angles differing from 110

$$\frac{\pi}{2}.$$

55 These phase-displacements can be obtained by all devices employed with this end in view; combining resistances, reactances, self or mutual inductances, capacities, transformers, short-circuited rings etc.

Fig. 11 represents the wiring diagram of 60 a wattmeter or of a wattmeter relay, the torque of which depends on the positive or negative phase sequence power component.

An electro-magnet acts on the disc D and 65 through the winding a of this electro-magnet flows a current proportional to the posi-

tive or negative phase sequence component of one of the three-phase voltages transformed into two-phase voltages by the Scott system S, of which 1 and 2 are the secondaries; s and r are more or less inductive circuits which produce the necessary phase displacements between the currents that flow through them and the voltages at their terminals.

The second winding is double, comprising two windings b and b' , combined with resistances r_1, r'_1 and reactances s_1, s'_1 ; T_1, T_2, T_3 are three current transformers. By suitably regulating the resistances and reactances, a value for the resulting ampere-turns is obtained proportional to the positive or negative phase sequence component of one of the currents and the phases can be regulated so that the torque is proportional to the active, reactive or complex power or the positive or negative phase sequence components of power. 80
85

The reactance coils and resistances in series can be completed by resistances and reactances shunted across the voltage coil or both across this latter and part of the reactances or again by other devices allowing the necessary phase displacements to be obtained. 90

Matters can also be arranged so that the balanced three-phase system is converted into a two-phase system unbalanced to a certain extent, which can facilitate obtaining the positive or negative phase sequence component. 95

One of the systems of values can be transformed into two-phase for example the voltages, and the other, for example the currents, left in three-phase form. 100

On the contrary, the voltages and currents can be transformed from three-phase to two-phase and the two negative (or positive) phase sequence components of the voltages can be acted upon by the two-phase currents themselves or vice-versa. It can be shown that, in these cases torques are likewise obtained depending on only the positive or negative phase sequence component of the power. 105
110

Fig. 12 shows the wiring diagram of a relay or wattmeter measuring the negative (or positive) phase sequence components of power: a and a' are two voltage windings; b, b' the current windings on the corresponding electro-magnets: D a disc: S a Scott transformer: T_1, T_2, T_3 three current transformers which feed b' with current proportional to the current i_3 of phase 3 and the coil b with current proportional to $(i_1 - i_2)$ the difference between the currents i_1 and i_2 of phases 1 and 2; $r, r', r_1, r_2, r'_1, r'_2, s_1, s'_1, s_2, s'_2, s, s'$ are resistances and reactances which produce the necessary phase displacements in order 115
120 to obtain the negative (or positive) phase sequence components of the two-phase voltages given by the secondaries 1 and 2 of the Scott system. 125

Fig. 13 is a wiring diagram for a watt- 130

meter or wattmeter relay measuring the negative phase sequence component of power in which two negative phase sequence components of ampère-turns are obtained 90° out of phase with each other, that is to say the two negative phase sequence components of a two-phase system of values proportional to the negative phase sequence components of the given three-phase voltage system, without transforming the three-phase voltage system into a two-phase system unbalanced to the same degree.

In this figure, 1, 2, 3 represent the three line wires of a three-phase circuit through which the currents i_1, i_2, i_3 flow; a, a_1 a double voltage winding of an electro-magnet, of which b is the current coil; a', a'_1, b' are the respective windings of a second electro-magnet; r, r'_1, r'_2 are resistances, s, s'_1, s'_2 are reactances, allowing resultant ampère-turns to be produced in a, a_1 proportional to the negative phase sequence component of the voltage $u_{1,2}$ and in a', a'_1 a component equal to

25 the preceding one and $\frac{\pi}{2}$ out of phase with

respect to it. In practice the current in a can be in phase with $u_{1,2}$, that in $a_1 60^\circ$ lagging $u_{1,2}$; the current in a' will lag $u_{2,1} 30^\circ$ and that in a'_1 , will lead $u_{1,3} 30^\circ$. T_1, T_2, T_3 represent three current transformers enabling ampère-turns in quadrature to be obtained in the current coils b and b' .

The desired phase displacements can be effected by windings short-circuited through variable resistances, said windings being associated with the voltage and current circuits and thereby affording means of acting on the phase displacements of the negative phase sequence components of the fluxes of the voltage circuits or on the fluxes of the current circuits.

The currents could also be combined in a manner differing from that indicated in the figure, without departing from the limits of the invention.

I claim:

1. Electroresponsive apparatus for a three-phase circuit including in combination two electro-magnets, three current transformers and a movable member on which said electro-magnets act, the primaries of said transformers being respectively connected to the phases of said three-phase circuit, one electro-magnet having a winding connected across the secondary of one of said transformers, and the secondaries of the remaining transformers being connected in opposition across a winding of the other electro-magnet.

2. Electroresponsive apparatus for a three-phase circuit including in combination two electro-magnets, three current transformers and a movable member on which said electro-magnets act, the primaries of said transformers being respectively con-

nected to the phases of said three-phase circuit, said electro-magnets being connected to said transformers to form part of a two-phase system which is balanced when said three-phase circuit is balanced.

3. Electroresponsive apparatus for a three-phase circuit including in combination an electro-magnet and a rotatable disc on which said electro-magnet acts, said electro-magnet having two cooperating windings respectively arranged on opposite sides of said disc, said windings being respectively connected to be energized in accordance with the currents in one phase conductor of the circuit and the difference between the currents in the other two phase conductors, the ampère-turns of said electro-magnet windings forming part of a two-phase system.

4. In combination with a three-phase circuit, electroresponsive apparatus including polyphase transforming means connected to be energized from the circuit, a movable member and actuating means therefor including two independent electro-magnets each arranged to exert a force on the member, the windings of said electro-magnets being connected to said transforming means to be energized respectively in accordance with the components of an electric quantity of a two-phase system having effective values dependent on the components of the corresponding electric quantity of the three-phase circuit.

5. In combination with a three-phase circuit, electroresponsive apparatus including polyphase transforming means connected to be energized from the circuit, a disc of electric current conducting material and actuating means therefor including two independent electro-magnets respectively arranged to exert additive torques on the disc, the windings of said electro-magnets being connected to said transforming means to be energized respectively in accordance with the components of the current of a two-phase system having effective values proportional to the components of the current of the three-phase circuit.

6. In combination with a three-phase circuit, electroresponsive apparatus including movable disc means and controlling means therefor including two electro-magnets inductively associated with said disc means and connected and arranged to exert thereon a torque proportional to $I_d^2 + I_i^2$, and electro-magnetic means inductively associated with said disc means and connected and arranged to exert thereon a torque proportional to $I_d^2 - I_i^2$, I_d and I_i being respectively the positive and negative phase sequence components of the current of said circuit.

7. In combination with a three-phase circuit, electroresponsive apparatus including a movable disc of electric current conducting material and actuating means therefor in-

- cluding two electro-magnetic elements inductively associated with said disc and connected to be energized from said circuit respectively in accordance with two components of an electric quantity displaced 90° in phase relation under balanced circuit conditions and having effective values dependent on the components of the same electric quantity of the circuit.
10. 8. In electroresponsive apparatus for a three-phase circuit, electro-magnetic means for exerting forces respectively dependent on the sum of and the difference between the squares of the positive and negative phase sequence components of the currents of a two-phase system derived from and unbalanced to the same extent as the three-phase circuit, and movable means arranged to be controlled in accordance with a resultant of said forces.
15. 9. In electroresponsive apparatus for a polyphase circuit, electro-magnetic means for exerting forces respectively dependent on two different predetermined functions of the phase sequence components of a system derived from and unbalanced to the same extent as the polyphase circuit and having a different number of phases, and a movable member controlled in accordance with a resultant of said forces.
20. 10. In combination with a three-phase circuit, electroresponsive apparatus including a movable disc of electric current conducting material and means for exerting thereon a torque proportional to the difference between the squares of the positive and negative phase sequence components of the circuit current including two cooperating electro-magnetic elements inductively associated with the disc on opposite sides thereof, the winding of one element being connected to be energized in accordance with the current in one phase conductor of the circuit and the winding of the other element being connected to be energized in accordance with the difference between the currents in the other two phase conductors.
25. 11. In combination with a three-phase circuit, electroresponsive apparatus including a movable disc of electric current conducting material and actuating means therefor including two electro-magnetic elements inductively associated with said disc and connected to be energized from the currents of said circuit by two currents respectively displaced 90° in phase relation under balanced circuit conditions and having effective values dependent on the currents of said circuit.
30. 12. In combination, a three-phase circuit, electroresponsive apparatus including a movable member of electric current conducting material, electro-magnetic means inductively associated with said member and arranged to exert thereon a torque dependent on a predetermined function of two of the phase sequence components of the current of said three-phase circuit and means for diminishing the effect of one of said components on said torque including electro-magnetic means inductively associated with said member and arranged to exert a torque dependent on a different predetermined function of said phase sequence components.
35. 13. In electroresponsive apparatus for a polyphase circuit, a movable member of electric current conducting material, electro-magnetic means inductively associated with said member and means connected to said circuit for exerting on said member a force dependent on a predetermined sum function of the phase sequence components of a system derived from and unbalanced to the same extent as the polyphase circuit and having a different number of phases.
40. 14. In combination, a three-phase circuit, electroresponsive apparatus including a movable member of electric current conducting material, electro-magnetic means inductively associated with said member and arranged to exert thereon a torque dependent on a predetermined function of two of the phase sequence components of the current of said three-phase circuit and means for diminishing the effect of one of said components on said torque including electro-magnetic means inductively associated with said member and arranged to exert a torque dependent on a different predetermined function of said phase sequence components.
45. 15. In electroresponsive apparatus for a polyphase circuit, a movable member of electric current conducting material, electro-magnetic means inductively associated with said member and means connected to said circuit for exerting on said member a force dependent on a predetermined sum function of the phase sequence components of a system derived from and unbalanced to the same extent as the polyphase circuit and having a different number of phases.
